UNITED STATES PATENT OFFICE.

LEWIS W. HARDY, OF CHICAGO, ILLINOIS, ASSIGNOR OF ONE-HALF TO
MELVILLE E. DAYTON, OF SAME PLACE.

OIL-CAN.

SPECIFICATION forming part of Letters Patent No. 551,893, dated December 24, 1895.

Application filed February 18, 1895. Serial No. 538,796. (No model.)

To all whom it may concern:

Be it known that I, LEWIS W. HARDY, a resident of Chicago, in the county of Cook and State of Illinois, have invented certain new and useful Improvements in Devices for Oiling Elevated Shaft-Bearings; and I do hereby declare that the following is a full, clear, and exact description thereof, reference being had to the accompanying drawings, and to the letters of reference marked thereon, which form a part of this specification.

This invention relates to oilers for oiling elevated shaft-bearings and the like; and it consists in the features and combinations hereinafter set forth and pointed out in the appended claims.

Figure 1 is a longitudinal section showing my invention in the form now believed to be the best adapted for general use. Fig. 2 is a longitudinal section showing the invention in modified form. Fig. 3 is a longitudinal section showing the general invention wanting certain features present in Figs. 1 and 2.

A represents a cylinder closed at both ends; B, a pole or handle of suitable length connected with the lower end of the cylinder A; C, a tube that slides through the upper head of the cylinder, and D a piston connected with the lower end of the tube C.

The cylinder A is provided with a filling-hole a stopped with a plug a' at its upper end, and the tube C is provided with an opening c near its connection with the piston D, while its upper end is provided with a hook C'.

In the simple construction shown in Fig. 3 the piston D fills the cylinder A. The cylinder A being filled with oil and the filling-hole stopped by the plug, the end of the hook C' on the tube C is thrust into the cup of an elevated bearing and downward-pulling force is applied to the handle B. Such pulling upon the handle draws the cylinder A downwardly while the piston remains stationary, thus contracting the space above the piston within the cylinder and causing the oil to pass into the opening c and out at the upper end of the tube into the cup or bearing to be supplied.

In the construction shown in Fig. 1 the piston D is a hollow cylinder, smaller than the cylinder A and having a closed bottom and

an opening d near its upper end. E is a fixed plug filling the cylinder A, but having holes e e by which oil may pass downward about and into the piston, and also having a cylindrical projection E' which enters the hollow open-topped piston D. Upon hooking the tube C into a bearing-cup and pulling the cylinder A downward, the feed-opening d of the hollow piston is first closed and the oil then confined in the piston is thereafter forced upward through the tube C into the bearing-cup to be supplied. A spring F depresses the piston D and the tube C, permitting the piston to again fill ready for another operation. The piston D, in this case, is a measuring device which limits the quantity of oil discharged at each stroke thereof, and the device having this provision is less likely to oversupply a bearing-cup and waste the oil.

In Fig. 2 essentially the same features are shown as are present in Fig. 1. The fixed head E is connected with the bottom plug A' of the cylinder A by a hollow cylinder E', which forms a cavity to be filled through an opening e, and the piston D, working in the cylinder E', upon being raised first closes the said inlet-opening and then expels the oil from said cylinder E' through the tube C, as in the construction shown in Fig. 1. Suitable openings e' admit and discharge oil to and from the cylinder E' beneath the piston to obviate a vacuum at this point. The bottom-plug A' closing the lower end of the cylinder A is shown as having a socket for the secure attachment of the pole or handle B and the top plug A' is shown as having the filling-hole formed therein and directed laterally to the cylinder, whereby the cylinder A may be filled when in a horizontal position.

While the construction shown in Fig. 3 is suitable for some places, the construction containing means for insuring a limited discharge of oil is preferable for most shops. When the bearing is small a single stroke of the piston may suffice, but when the bearing is large two or more strokes may be made to properly supply it. By arranging the end of the hook C' in, or proximately in, line with main or straight portion of the tube C to which it belongs, the draft on the tube is made more direct in its guide and danger of binding the tube is less-

ened, while the provision of a side hole *c* near the open discharging end of the tube insures discharge of the oil even though the end of the tube shall happen to press against any object tending to close said end opening. If desired the hook may obviously be a separate piece attached to the tube. Other changes may also be made without departure from my invention.

10. I claim as my invention--

1. In an oiler, the combination with an oil receptacle, of a piston, a delivery tube connected with the piston and protruding from the receptacle, and a hook connected with the outer end of the delivery tube, whereby, the hook of the tube being engaged with a bearing cup to be supplied and the tube drawn out by retraction of the receptacle, oil is expelled through the tube, substantially as described.

2. An oiler for elevated bearings and the like, comprising a receptacle and pump mounted on the end of a pole or handle, the pump piston being connected with a protruding, longitudinally movable delivery tube which is provided with a hook adapted to be engaged with the cup or bearing to be supplied, whereby, first, the oiler may be raised to engagement with the elevated bearing by the operator standing below, and, second, upon a downward pulling movement of the pole or handle by the operator, the pump is operated and the oil is expelled through the tube to the cup or bearing, substantially as set forth.

3. In an oiler for elevated bearings, the combination of a receptacle closed at both ends and provided at its lower end with means for its attachment to a pole, a pump piston with-
40 in the receptacle, and a delivery tube connected with the piston and protruding through the upper end of the receptacle, said delivery tube being provided at its delivery end with a hook adapted to be engaged with the cup or
45 bearing to be supplied, whereby, the hook being so engaged, a downward pulling force applied to the receptacle causes the piston

to expel oil through the delivery tube to the bearing.

4. An oiler for elevated shaft bearings, the combination of a receptacle adapted to be mounted on a pole, a pump piston within the receptacle, a delivery tube connected with the piston and protruding through the upper end of the receptacle, said delivery tube terminating in a hook-formed spout at its upper end, the extremity of which is substantially in line with the straight portion of the tube, and a spring arranged to retract the delivery tube, substantially as and for the purposes set forth.

5. An oiler comprising a receptacle closed at both ends, a handle secured to the receptacle, a separate piston pump secured within and at or near the bottom of the receptacle, a delivery tube connected with the piston of the pump and protruding through the top of the receptacle, said tube terminating at its outer end in a hook-formed spout, and a spring for retracting the delivery tube.

6. In an oiler, the combination of a receptacle closed at both ends, an apertured diaphragm secured within the receptacle and provided with a downwardly projecting plug having a lengthwise passage through it; a hollow piston fitted to the plug and provided with a lateral opening which is covered by the plug except when the piston is retracted; a delivery tube connected with the bottom of the piston, said tube having an opening within the piston, protruding through the plug and also through the top of the receptacle, and having a hook-formed spout at its upper end, and a spring for retracting the piston and delivery tube, substantially as described and for the purposes set forth.

In testimony that I claim the foregoing as my invention I affix my signature in presence of two witnesses.

LEWIS W. HARDY.
